UNITED STATES PATENT OFFICE.

DONALD STEWART KENNEDY, OF NEW YORK, N. Y.

RESILIENT WHEEL.

Application filed April 23, 1921. Serial No. 463,872.

To all whom it may concern:

Be it known that I, DONALD STEWART KENNEDY, a citizen of the United States, and a resident of the city of New York, borough 5 of the Bronx, in the county of Bronx and State of New York, have invented a new and Improved Resilient Wheel, of which the following is a description.

My invention relates to resilient wheels 10 and more particularly to the wheels of motor vehicles.

The general object of my invention is to provide an improved wheel of the indicated type efficient in affording resiliency while 15 possessing the maximum stability, and to provide a wheel wherein the deformation of the resilient elements at a given point under an imposed load or due to shock, will be widely distributed circumferentially of the 20 wheel.

The nature of the invention and its advantages and distinctive features will clearly appear as the description proceeds.

Reference is to be had to the accompanying drawings forming a part of this specification, it being understood that the drawings are merely illustrative of practical examples of the invention.

Figure 1 is a partly sectional side elevation of the greater portion of a wheel embodying my invention;

Figure 2 is an enlarged transverse section on the line 2—2, Figure 1;

Figure 3 is an enlarged detail view of a 35 portion of the wheel shown partly in side elevation and partly in section, taken in the plane of the wheel;

Figure 4 is a view similar to Figure 3 but illustrating a modified arrangement of 40 parts.

Referring at first more particularly to Figures 1 to 3, the letter A indicates portions of a wheel which may be of any approved form, B indicating the felly; C, the 45 usual fixed rim thereon of known form, and D and E the lugs and their securing bolts, all of which may be of any approved construction.

In accordance with my invention I provide 50 an inner rigid rim 10 of unbroken continuity and advantageously slightly dished or channeled adapted to be held by the lugs D and the flange of the fixed rim C, or

other suitable means to demountably secure said rim 10. Between the inner and 55 outer rims I provide interposed resilient means including an annular resilient floating element 13 sustained for flexure radially inward or radially outward at all points about said element through the medium of bowed springs 15 interposed between an inner band 11 and the adjacent annular floating element and additional annular series of bowed springs 15^a outside of said floating element. 60

In the form shown in Figures 1 to 3 the outer annular series of bowed spring members 15^a are secured to the floating element 13 and at points remote from the connection with said floating element, said spring 70 members being connected with an outer band 14.

The inner band 11 is secured to the inner rim 10 by suitable means preferably by rivets 16 passing through said rim 10 and 75 band 11 and through interposed spacing blocks 16^a so that said band 11 may flex between the rivets 16 and relatively to the rim 10.

The outer rim 12 is secured at intervals to 80 the annular resilient band 14 in a way to space the latter, for which purpose, in Figures 1 to 3, spacing blocks 17 are employed through which are passed rivets 18 which also pass through said outer rim 12 and said 85 band 14. The sinuous element forming the spring members 15 is bowed alternately toward the inner annular band 11 and toward the floating element 13 and the bows or spring members are secured alternately to 90 said element 13 and to the band 11 at points remote from each other by rivets 19, 20. Similarly, the sinuous element forming spring members 15^a is bowed alternately to 95 toward the floating element 13 and toward the outer band 14, the bows or spring members 15^a being secured alternately to said floating element 13 and band 14 at points remote from each other by rivets 21, 22 or by brazing or other suitable means.

In Figure 4 the inner and outer bands 11 and 14 are omitted. The outer springs 15^b corresponding with springs 15^a are secured to the floating element 13 by rivets 21^a and directly to the tire rim 12^a corresponding 105 with rim 12 by rivets 22^a. The inner springs

15° corresponding with springs 15 are secured by the described rivets 20 to the floating element 13 and they are secured directly to the rim 10 by rivets 16° passing through 5 spacing blocks 16° between said springs 15° and said rim 10.

By the use of the floating annular resilient element between the inner and outer rims and the sinuous elements forming both 10 bowed springs at the inside and outside of the floating element, a depression of the outer rim is effective through the band 14 on the bowed springs 15° and floating element 13 and from the latter to the spring members 15. By the provision of the sinuous elements 15, 15° and the floating annular element 13, the deformation and stresses are distributed 15 annularly of the wheel through the bows of the sinuous elements and the floating annular 20 element for essentially one-half the wheel instead of being localized by exerting the depressing force through resilient elements almost directly to the inner rim of the wheel.

Separate tread blocks 23 are employed in 25 practice on the rim 12, or 12°, to constitute a cushion tire. Said tire-receiving rim 12 (or 12°) is resilient. On said rim at the sides are series of separate flanges 24 at each side the separation of the flange members permitting 30 flexure of the rim. On said rim also are produced at intervals larger flanges 25 through which bolts 26 pass, said bolts passing also through clamp blocks 27 preferably of metal and preferably of elliptical or ob- 35 long form to present a broad bearing surface which clamps flanges 28 formed on adjacent separate tread blocks 23 at the bases of the tread blocks. Formed in the face of the blocks 23 may be cup-like depressions 29 to 40 give adhesion and prevent skidding and to make blocks more yielding.

I would state in conclusion that while the illustrated examples constitute practical embodiments of my invention, I do not limit 45 myself strictly to the mechanical details herein illustrated, since manifestly the same can be considerably varied without departure from the spirit of the invention as defined in the appended claims.

Having thus described my invention, I 50 claim:

1. In a resilient wheel, an inner rim adapted to be mounted on a wheel, an outer tire rim, a continuous annular band secured at 55 intervals to said inner rim and spaced therefrom to flex between the securing means, a continuous annular resilient floating element outside of and spaced from said band, springs disposed between said band and floating element, and springs outside of said floating element and bearing thereon, said second-mentioned springs being subject to depression of the wheel tread.

2. In a resilient wheel, an inner and an 60 outer rim, and interposed non-sinuous re-

silient elements extending continuously about the inner rim between the same and the outer rim and spaced from each other, the innermost element being spaced from the wheel rim to afford clearance for flexure, 70 and springs disposed between adjacent resilient annular elements.

3. In a resilient wheel, an inner rim adapted to be secured to a wheel, an outer rim, 75 an annular non-sinuous resilient element between said rims, and annular sinuous resilient elements of unbroken continuity within and outside of the first-mentioned annular element and alternately secured to the latter and to the rims, said sinuous elements 80 floatingly sustaining the first-mentioned annular element, the outer sinuous element being subject to the depression of the wheel at the tread.

4. In a resilient wheel, an inner rim, means 85 to mount the same, an outer rim, an annular resilient non-sinuous element between said rims, and annular sinuous elements within and outside of said non-sinuous element and floatingly sustaining the same, the 90 outer sinuous element being subject to depression of the outer rim.

5. In a resilient wheel, an annular band, a floating annular non-sinuous resilient element outside of said band, a resilient sinuous 95 element of unbroken continuity between said band and floating element and having the bends thereof secured alternately to the band and to the floating element, a sinuous 100 annular resilient element of unbroken continuity outside of the floating element, means securing the alternate bends of said outer sinuous element to said floating element, an annular element outside of the outer sinuous element, and means to secure 105 said outer element to the outer sinuous element at the remaining bends thereof.

6. In a resilient wheel, a resilient tire rim, an inner rim adapted to be mounted on the wheel, means resiliently sustaining the tire 110 rim, said tire rim having separate flange members at the side edges thereof and having at intervals larger flanges, tread blocks mounted on said tire rim and presenting flanges at their opposed ends at the bases of 115 said blocks, transverse clamp blocks bearing on the end flanges of the tread blocks, and transverse bolts passing through said larger flanges of the tire rim and through said clamp blocks.

7. In a resilient wheel, an inner rim adapted to be secured to a wheel, an outer tire rim, an annular non-sinuous resilient floating element between said rims and separated therefrom, and sinuous resilient elements presenting each an annular series of bowed springs respectively outside of and within said floating element, and means connecting said springs of the sinuous elements 125 at intervals respectively with the inner and 130 outer rim.

outer rims and with said floating element.

8. In a resilient wheel, an inner rim adapted to be mounted on a wheel, an outer tire rim, an annular non-sinuous resilient floating element between and spaced from said rims, a continuous sinuous element presenting bowed springs and disposed between the

inner rim and said floating element and secured alternately to each, and an outer continuous sinuous element presenting bowed members secured alternately to said floating element and to said outer rim.

DONALD STEWART KENNEDY.
